BOBBIN-STRIPPER.

1,300,004.

Specification of Letters Patent.

Patented Apr. 8, 1919.

Application filed May 29, 1916. Serial No. 100,474.

To all whom it may concern:

Be it known that I, BURT A. PETERSON, a citizen of the United States, residing at Rockford, in the county of Winnebago and State of Illinois, have invented certain new and useful Improvements in Bobbin-Strippers, of which the following is a specification.

The object of this invention is to provide improved means for stripping waste yarn from bobbins.

In the accompanying drawings, Figure 1 is a side elevation of a bobbin stripper embodying the features of my invention. Fig. 2 is an enlarged sectional view taken in the plane of dotted line 2-2 of Fig. 1. Fig. 3 is a fragmental upper side view. Fig. 3^a is a fragmental view of certain parts shown in the left-hand portion of Fig. 3. Fig. 4 is a section on line 4 of Fig. 1. Fig. 5 is a sectional view taken in the plane of dotted line 5-5 of Figs. 1 and 6. Fig. 6 is a view taken in the plane of dotted line 6 of Fig. 5. Fig. 7 is a detail view of one of the stripping elements.

The invention is susceptible of embodiment in bobbin strippers which are entirely independent, in structure and source of power, of any other machine, but for convenience in operation the bobbin stripper may, if desired, be associated with a winder for rewinding yarn from tailings bobbins, that is to say, bobbins which it has been impracticable to unwind fully in an automatic winder of the type shown, for example, in Patent No. 1,175,710, dated March 14, 1916. While tending such a tailings winder the operator may in spare time operate the bobbin stripper to remove from bobbins yarn which it is impracticable to unwind on the tailings machine.

The bobbin stripper comprises stripping elements arranged to embrace a bobbin just above the butt thereof, and means to produce relative movement between the bobbin and the stripping elements. In the present embodiment the stripping elements are relatively stationary, and means is provided to force the bobbin through the space between the stripping elements whereby to strip the yarn from the bobbin. In the construction selected for illustration, the stripping elements partake of the general form of an iris diaphragm, being contractible to closely

embrace the body of the bobbin so as to detain the waste yarn as the bobbin is forced through the diaphragm.

The iris diaphragm comprises six stripping elements or blades 2 (Figs. 5 and 7), each provided at one end with a pivot 3 which is mounted in a bearing 4 (Fig. 6) in a stationary plate or web 5. The plate 5 has an opening 5^a therein. The bearings 4 are equidistantly spaced from each other and are arranged around the opening 5^a. The opposite end of each blade 2 is provided with a pivot 6 which is mounted within a radial slot 7 in a disk 8, said disk having a central opening 8^a which is alined with the opening 5^a. The disk 8 is supported by a tubular hub 9 which is rotatably mounted in a bearing 10. It will be seen that when the disk 8 is oscillated, the stripping blades 2 will be swung to enlarge or diminish the space between them. Coacting stop shoulders 2^a on the blades 2 limit the inward or contractile movement of the blades.

The means for turning the disk 8 in the direction to contract the iris diaphragm comprises a tension spring 11 (Fig. 5), acting upon a pin 12 fixed to said disk. The means for turning the disk 8 in the direction to expand the iris diaphragm comprises a bell-crank lever 13 pivoted at 14, one arm of said bell-crank lever underlying the pin 12 and the other end being connected by means of a link 15 to one arm of a bell-crank lever 16 which is pivoted at 17 to the supporting frame. The supporting frame comprises a bed 18. The bell-crank 16 is arranged to be swung in the direction to cause enlargement of the iris diaphragm by means of a reciprocatory bar 19 which is rigidly connected to a plunger 20 for forcing the bobbin through the diaphragm. In the present embodiment said bar and plunger are arranged to be reciprocated by power derived from a constantly-rotating shaft 21 of the tailings winder. The operative connection between the shaft 21 and the bobbin-stripper comprises a pinion 22 rotatably mounted on said shaft and yieldingly driven by a spring-pressed clutch member 19^a splined to the shaft. The pinion 22 is arranged to mesh alternately with two opposed racks 23 and 24 formed upon the bar 19 and the plunger 20, respectively. In order that the racks may be alternately

5 moved into mesh with the pinion 22, the supporting frame or bed 18 is pivotally supported as at 25 (Fig. 1), said bed normally resting against a bell-crank lever 26 which is pivotally supported at 27. One arm of the bell-crank lever carries an anti-friction roller 28, that bears against the lower side of the bed 18, while the other arm of the bell-crank lever is arranged to bear against 10 an adjustable stop consisting of a screw 29 carried by the bed 18. The means for moving the bell-crank 26 comprises a treadle 30 connected to the said bell-crank lever through a link 31.

15 The bar 19 and the plunger 20 are secured together in parallel relation by means of rivets 32 and 33 which are integral with spacing members 34 and 35, respectively. Said bar and plunger are mounted for sliding movement in a guide 36, (Figs. 1 and 4). At the upper end of the rack 23 is a blank space 37, and at the lower end of the rack 24 is a blank space 38. Downward movement of the bar 19 and plunger 20 is limited 25 by contact of the spacing member 34 with a stop bracket 36^a secured to the guide 36. When the parts 34 and 36^a are in contact, the blank space 37 is opposite the pinion 22.

20 Normally the stop 29 is in contact with the bell-crank lever 26, and the pinion 22 is out 30 of mesh with the rack 23 and is opposite the blank space 38. To contract the iris diaphragm and force the bobbin through the diaphragm the operator depresses the treadle 30, thereby moving the rack 23 into mesh 35 with the pinion 22.

25 The bell-crank lever 16 carries an anti-friction roller 39 (Fig. 3) which is arranged to roll in contact with the upper end portion 40 of the bar 19. Opposite the roller 39 is a roller 40 on the bed 18 to support the bar 19 against the thrust of the roller 39. There is a notch 41 (Fig. 3^a) in the bar 19 in which the roller 39 may lie for a purpose to be described hereinafter.

30 To the lower end of the plunger 20 is removably secured a head 42 having a rounded stud 43 arranged to enter the recess in the tip end of the bobbin, an annular shoulder 50 44 arranged to bear against the end of the bobbin, and a cylindrical portion 45 of less diameter than the tip of the bobbin. The head 42 shown in the drawing may be removed and replaced by another head of suitable 55 length and form properly to engage a bobbin of different length or shape from the one herein illustrated.

35 In the plate 5 is formed an upwardly-flaring annular recess 46 to receive the yarn 60 stripped from the bobbin.

40 Above the iris diaphragm is a guide 47 to receive a bobbin to be stripped. At the inner side of said guide are two flanges 48 (Fig. 2) arranged to support the bobbin in 65 approximately axial alignment with the dia-

phragm. To support the bobbin against longitudinal movement prior to the descent of the plunger, I provide a detent 49 (Figs. 1 and 2) which is fixed to a rock-shaft 50 and which is yieldingly held in operative position by means of a coiled spring 51 acting upon a crank-arm 52 fixed to said shaft. 53 is a stop-pin with which the crank arm normally lies in contact.

45 At the forward side of the lower end of the guide 47 is a wall 54 coacting with the remainder of the guide to form a socket into which the butt-end of the bobbin is inserted by the operative.

50 To prevent the yarn from clinging to and ascending with the plunger, I provide two stripper springs 55 (Figs. 2 and 6) lying at opposite sides of the path of movement of the bobbin and just above the recess 46.

55 Assuming the parts to be in the position shown in Fig. 1, the operation is as follows: The operative places a bobbin in the guide 47 with the butt of the bobbin lying behind the wall 54. The operative then depresses the treadle 30, thereby rocking the bed 18 so as to place the rack 23 in mesh with the pinion 22. The plunger 20 then descends, forcing the bobbin past the detent 49. By the time the butt of the bobbin has passed through the iris diaphragm, the upper end of the bar 19 has passed the roller 39, whereupon the spring 11 contracts the diaphragm into engagement with the bobbin just above the butt thereof. In the continuing movement of the bobbin the yarn is scraped off the bobbin by the diaphragm. When the tip of the bobbin has passed the diaphragm the latter contracts still further to the extent permitted by the stop shoulders 2^a. The bobbin drops into a suitable receptacle (not shown) as soon as it has passed the diaphragm, unless there should be frictional engagement between the stud 43 and the bobbin, in which event the bobbin will be stripped from the stud 43 by the diaphragm when the plunger begins to ascend. The waste yarn falls through the diaphragm and through the tubular hub 9, or is pushed therethrough by the next succeeding bobbin.

60 When the downward stroke of the plunger is completed, the blank space 37 is opposite the pinion 22. When the operative releases the treadle 30, the bed 18 rocks to carry the stud 29 into contact with the bell-crank lever 26, whereby the upper end of the rack 24 is placed in mesh with the pinion 22. The bar 19 and the plunger 20 are then returned to their normal upper position. When the upper end of the bar 19 strikes the roller 39, the bell-crank lever 16 is turned to enlarge the iris diaphragm. When the blank space 38 arrives opposite the pinion 22, the roller 39 moves into the notch 41 in the bar 19 under the action of the spring 11 operating through the bell-crank lever 13 and the link 130

15. The roller 39 lying within the notch 41 holds the bar 19 and the plunger 20 up so that the lowermost tooth of the rack 24 is clear of the constantly-rotating pinion 22.

5 If excessive resistance should be encountered by the plunger 20 in its descent, breakage is avoided through slippage of the pinion 22 on the shaft 21, the clutch member 19^a yielding to allow the shaft to rotate with relation to the pinion.

10 The guide 47 is of such limited width as to prevent the operative from inserting bobbins carrying a much larger yarn load than it is intended shall be removed by stripping. 15 The dimensions of the guide also are such as to prevent the operative from placing her hand in the path of movement of the plunger.

I would have it understood that the invention is not limited to the construction herein shown, the present embodiment being susceptible of considerable modification within the scope of the appended claims.

I claim as my invention:

25 1. A bobbin stripper having, in combination, a bobbin guide; an expandable and contractible annular stripping device at one end of the guide; a yieldable detent located in the path of a bobbin about to enter said device; a plunger for forcing the bobbin past the detent and through said annular device; and a yieldable member located adjacent to the detent and arranged to bear against the side of the bobbin and the plunger to prevent the yarn from clinging to the plunger.

30 2. A bobbin stripper having, in combination, a pivoted bed, a stripping element mounted on the bed, a plunger guided for reciprocation upon the bed for pushing a bobbin past the stripping element, two opposed racks attached to the plunger, a constantly rotating shaft, a pinion mounted on said shaft between the racks, and means for pivotally moving the bed to place the racks 35 alternately in mesh with the pinion.

35 3. A bobbin stripper having, in combination, a supporting frame; a stripping element on the frame; means to move the stripping element into engagement with a bobbin; a lever pivoted on the frame; connections from the lever to the stripping element for moving the latter out of position to engage a bobbin; a plunger for forcing a bobbin past the stripping element; two opposed rack bars attached to the plunger; a constantly rotating shaft; a pinion mounted on said shaft between the rack bars; and means to cause the rack bars to mesh alternately with the pinion, said lever bearing 40 against one of said rack bars, the last mentioned rack bar moving out of engagement with said lever when the butt of the bobbin has passed through said annular device.

45 4. A bobbin stripper having, in combination, a plate having an opening there-

through; a disk having a central opening; a tubular hub pivotally supporting said disk, said openings and hub being axially aligned; an expandable and contractible annular device located between said plate and disk and comprising blades pivoted on said plate and movable by said disk; means for oscillating the disk; and means for moving a bobbin through said openings and hub.

5 5. A bobbin stripper having, in combination, a stripping element, stationary means for supporting a bobbin at one side of the stripping element with the butt of the bobbin extending toward the stripping element, means for forcing the bobbin off said supporting means and to the other side of the stripping element, and means for moving the stripping element into engagement with the bobbin after the butt of the bobbin has passed the stripping element.

6. A bobbin stripper having, in combination, a bobbin guide, an expandable and contractible annular stripping device at one end of the guide, a yieldable detent located in the path of a bobbin about to enter said device, a plunger for forcing the bobbin past the detent and through said annular device, and means for contracting said device into contact with the bobbin immediately after the butt of the bobbin has passed through said device.

7. A bobbin stripper having, in combination, a member having an opening therethrough, a plurality of stripping blades pivoted about said opening, a disk having an opening aligned with the first mentioned opening, said disk having slots therein, said blades having studs lying in the slots, means for oscillating the disk to move the blades toward and away from the axis of said openings, and means for pushing a bobbin butt first through said openings.

8. A bobbin stripper having, in combination, an expandable and contractible annular device, means for producing relative movement between the device and a bobbin to strip yarn from the bobbin, and means for contracting the device into engagement with the bobbin after the butt of the bobbin has passed through the device.

9. A bobbin stripper comprising, in combination, an expandable and contractible annular device, a spring for contracting the device into engagement with a bobbin, means for moving a bobbin through the device, and means for releasing the spring to action after the butt of the bobbin has passed through the device.

10. A bobbin stripper having, in combination, an expandable and contractible annular device, a spring tending to contract the device, a lever arranged to enlarge the device, a plunger for pushing a bobbin through the device, and a member moving with the plunger and arranged to operate said lever.

11. A bobbin stripper having, in combination, a bobbin guide, a stripping device, a plunger having a forward end portion of less diameter than the tip of a bobbin and having a stud adapted to enter the recess in the tip of a bobbin, means for actuating the plunger to push a bobbin past the stripping device, and spring-actuated means for moving the stripping device into contact with a bobbin, the stripping device moving into contact with the reduced end portion of the plunger when the bobbin has passed the stripping device, said device serving to strip the bobbin from said stud upon the return movement of the plunger.

12. A bobbin stripper having, in combination, a stationary inclined bobbin guide; a stripping device at the lower end of the guide; a yieldable detent located in the path 20 of the bobbin above said device; and a plunger for forcing the bobbin off the guide and past the detent and the stripping device.

13. A bobbin stripper having, in combination, a plate having an opening there-through; a pivoted disk having a central 25 opening; said openings being axially alined; an expansible and contractible annular device located between said plate and disk and comprising blades pivoted on said plate and movable by said disk; means for oscillating the disk; and means for moving a bobbin through said openings.

14. A bobbin stripper having, in combination, a stationary bobbin guide, an expansible and contractible annular stripping device at one end of the guide, a plunger for forcing the bobbin off said guide and through said annular device, and means for contracting said device into contact with the bobbin immediately after the butt of the 40 bobbin has passed through said device.

In testimony whereof I have hereunto set my hand.

BURT A. PETERSON.
